UNITED STATES PATENT OFFICE.

ELMUS E. WEAVER, OF BOISE, IDAHO, ASSIGNOR TO WEAVER SPRING COMPANY, OF BOISE, IDAHO, A CORPORATION OF IDAHO.

SPRING SUSPENSION FOR VEHICLES.

1,401,841.

Specification of Letters Patent. Patented Dec. 27, 1921.

Application filed July 18, 1919, Serial No. 311,759. Renewed September 13, 1921. Serial No. 500,437.

To all whom it may concern:

Be it known that I, ELMUS E. WEAVER, a citizen of the United States, residing at Boise, in the county of Ada and State of Idaho, have invented new and useful Improvements in Spring Suspensions for Vehicles, of which the following is a specification.

The present invention relates to spring suspensions for vehicles of various kinds, it being particularly adapted for use, however, as a spring suspension for automobiles. The primary object of the invention is to provide a novel and improved spring suspension which will avoid numerous objections which have been found to exist with spring suspensions as heretofore used, the spring suspension of the present invention eliminating or minimizing the breakage of the springs, it embodying means whereby the strength of the springs may be regulated according to the load carried or to be carried by the vehicle, it enables the different wheels of the vehicle to act automatically and independently of one another when passing over uneven surfaces, thus improving the riding qualities of the spring suspension, and it also embodies means by which the driver of the vehicle is informed of the amount of tension for which the springs are set.

To these and other ends, the invention consists in certain improvements and combinations and arrangements of parts all as will be hereinafter more fully described, the features of novelty being pointed out particularly in the claims at the end of the specification.

In the drawings:—

40 Figure 1 is a top plan view of the chassis of an automobile or motor vehicle equipped with a spring suspension constructed in accordance with the present invention, the load weighing means being omitted.

45 Fig. 2 is a side elevation of the chassis as shown in Fig. 1.

Fig. 3 represents a vertical section taken longitudinally through the chassis as shown in Figs. 1 and 2.

50 Fig. 4 represents a transverse section of the chassis on the line 4—4 of Fig. 1.

Fig. 5 is a detailed view of the indicator which informs the driver of the amount of tension for which the springs are set.

55 Fig. 6 is a detail sectional view showing

the operative connection between one of the spring tensioned rock shafts and one of the arms which transmits the spring tension of such shaft to the respective wheel.

Fig. 7 is a detail view showing in elevation and as viewed from the rear the mechanism for regulating the tension of the springs by power derived from the motor which propels the vehicle.

Fig. 8 is a side elevation of the mechanism as viewed from the left in Fig. 7.

Fig. 9 is a top plan view of the spring regulating mechanism as shown in Figs. 7 and 8.

Fig. 10 represents a section on the line 70 10—10 of Fig. 7.

Fig. 11 is a top plan view of a vehicle having a spring suspension constructed in accordance with the present invention and embodying a device for weighing the load 75 on the vehicle and also means operative manually by the driver for regulating the strength of the springs according to the load.

Fig. 12 is a side elevation of the vehicle 80 as shown in Fig. 11.

Fig. 13 represents a section on the line 13—13 of Fig. 12 and looking in the direction of the arrows.

Similar parts are designated by the same 85 reference characters in the several views.

Spring suspensions constructed in accordance with the present invention are applicable generally to vehicles of all kinds and it should be understood that in some instances some of the features of the invention might be omitted and yet the principal advantages of the invention will be obtained. The invention, however, is especially adapted to fulfil the requirements of spring 90 suspensions for automobiles and other motor vehicles, the invention presenting many advantages and overcoming many defects as compared with automobile spring suspensions as heretofore used. The preferred 95 embodiment of the invention is shown in the accompanying drawings and will be herein-after described in detail. It is to be understood, however, that the invention is not restricted to the precise construction shown 100 as equivalent constructions are contemplated and will be included within the scope of the claims.

In the construction shown, 1 designates the main frame or chassis of an automobile 110

or motor vehicle. This frame may be of any suitable construction, it having a generally rectangular form as shown. 2-2 and 3-3 represent, respectively, pairs of front and 5 rear wheels, the rear wheels which are utilized in an automobile for propulsion being connected to shafts driven from a differential 4 which may be similar to that used at present for the same purpose. Power is 10 transmitted from an engine, which is not shown but is located in the forward part of the frame, to the differential by a propeller shaft 5, the forward end of this propeller shaft being connected in the usual or any 15 suitable way to the flywheel 6 of the engine. The housings 7 and 8 for the pairs of front and rear wheels extend transversely beneath the forward and rear portions of the frame and these axle housings may be guided relatively to the frame to prevent lateral displacement of the wheels with respect to the 20 frame by pairs of standards 9 and 10. The front and rear axle housings 7 and 8 are also connected by longitudinal rods 11 and 12 25 which serve to maintain the front and rear axle housings in parallelism, it being understood that each end of each axle housing is capable of moving independently in a direction toward and from the frame to conform 30 with irregularities in the surface over which the vehicle travels.

The spring suspension according to the present invention comprises a pair of rock shafts 13 and 14 which are journaled in the 35 sides of the frame, the ends of these shafts projecting outwardly from the opposite sides of the frame and are there provided with radially projecting pins or projections 15 and 16, respectively. Pairs of arms or 40 bars 17 and 18 connect the rock shafts 13 and 14 to the respective front and rear axle housings. These bars, as shown in Fig. 6, are each provided with a cylindrical head 19 which fits over the respective end of the 45 corresponding rock shaft, the head being formed with a segmental slot 20 to receive the corresponding pin or projection 15 or 16, as the case may be. Clevises 21 and 22 fixed to the front and rear axle housings respectively, serve to connect the rods 17 and 18 thereto, these rods being preferably connected pivotally to the clevises as shown. By this arrangement it will be understood 50 that relative vertical movements between the wheels and the frames will cause corresponding partial rotations of the rock shafts. The springs employed are preferably coil springs. A suitable number of coil springs 23 of appropriate size and length are provided for the suspension of the front portion 55 of the frame and a suitable number of these coil springs 24 of appropriate size and length are provided for the suspension of the rear portion of the frame. The coil springs 23 for the suspension of the front

portion of the frame are placed between a pair of draw bars 25 and 26, the opposite ends of the springs abutting against these respective bars. The draw bars are suitably guided to move longitudinally in the frame 70 they being shown in Fig. 4 as having reduced ends 27 which fit and slide in longitudinal slots 28 formed in the opposite side members of the frame. A suitable number of draw rods 29 and 30 extend through the 75 draw bars 25 and 26, the draw rods preferably extending longitudinally through the coil springs, thus serving as guides and supports for the springs. One end of each draw rod is provided with a fixed head 31 80 and the opposite end of each draw rod is provided with a longitudinally adjustable head 32, the adjustable heads being connected to the respective draw rods in any suitable way, as for example, by threading them on the respective draw rods. The draw rods fit loosely in both draw bars in order that they may move longitudinally therein. As shown the fixed heads 31 of the draw rods 29 are connected by cables 33 to the front rock shaft 13, these cables being partially wound upon the rock shaft. The fixed heads of the draw rods 30 are connected by cables 34 to a revoluble spring tensioning shaft 35, the latter preferably extending transversely of the main frame and being revoluble therein, the cables 34 being partially wound upon this spring tensioning shaft. In practice, the shaft 35 is rotated 100 in the proper direction by a crank applied to the angular end 36 of the shaft, to wind the cables 34 to the proper extent upon this shaft 35. The shaft 35 could be held in any set position of adjustment by a ratchet wheel 37 fixed thereon, and a dog or pawl 38 arranged to engage the teeth of the ratchet wheel. The winding of the cables 34 on the shaft 35 draws the draw rods 30 rearwardly, the heads 32 on the forward ends of these draw rods being thus caused to abut against 110 the draw bar 25 to move the draw bar rearwardly or toward the rear draw bar 26, such movements of the draw bar 25 causing more or less compression of the springs 23 which are interposed between the two draw bars 115 and the action of these springs is to force the rear draw bar 26 rearwardly. The force acting rearwardly upon the draw bar 26 is transmitted to the draw rods 29 and the rearward force thus applied to the draw rods 29 is transmitted, through the cables 33, to the rock shaft 13, in consequence of which the shaft 13 receives a force which tends to rotate the arms 17 in a direction to lift the front of the frame. This force, 120 however, is a yielding one and hence relative vertical movements may occur between the wheels and the frame to compensate for irregularities in the surface over which the vehicle travels.

Suitable means is provided for indicating to the driver of the vehicle the amount of tension for which the springs are set. As shown, such means comprises a rod 39 connected at its rear end to the front draw bar 25, this rod being guided to shift longitudinally of the frame in accordance with variations in the position of the draw bar 25 due to the different adjustments that may 5 be given the shaft 35. This bar 39 carries a cam 40 which in the present instance is in the form of a wedge, the inclined face of this cam coöperating with the lower end of a rack 41 which is suitably guided to reciprocate vertically, the teeth of the rack meshing with a pinion 42; the pinion being fixed to a shaft 43 which carries a pointer or indicator 44. A suitable graduated dial 45 is mounted on an appropriate support 46 10 connected to the main frame and it coöperates with the pointer 44 to indicate the different tensions applied to the springs 23 by adjustments of the spring tensioning shaft 35. A turn buckle 47 or equivalent 15 device is provided for adjusting the length of the rod 39 in order that the pointer 44 may read correctly on the dial in accordance with the different adjustments for which the springs are set.

The spring suspension for the rear portion of the frame is generally similar to that described for the front portion of the frame. It comprises a suitable number of springs 123 which are preferably of the 20 coil type and are interposed between front and rear draw bars 125 and 126, these draw bars being guided to shift longitudinally in the frame. Also draw rods 129 and 130 extend through the draw bars, the fixed heads 131 of the draw bars 129 being connected by cables 133 to the shaft 14 which coöperates with the rods or bars 18 and the fixed heads 131 of the draw rods 130 are connected by cables 134 to a shaft 135 which extends transversely to the frame and is journaled therein. The draw rods 129 and 130 in this instance also are provided with adjustable heads 132. The spring tensioning shaft 135 for the rear portion of the frame 25 is preferably provided with means for adjusting it to increase or decrease the tension of the springs for the rear portion of the frame to conform with the different loads carried by the vehicle by hand power or by power derived from a motor which propels the vehicle. As shown, the power adjusting means for the spring tensioning shaft 135 comprises a worm wheel 47^a fixed on the shaft 135, a worm 48 fixed on a 30 shaft 49 which extends to the forward portion of the frame, gearing 50 which connects the shaft 49 to a shaft 51 journaled in a bracket 52 and a supplemental shaft 53 which is connected to the shaft 51 by a universal joint 54 and embodies means for

transmitting motion from the motor to the shaft 49. The power may be taken in different ways from the motor which propels the vehicle. As shown, a friction wheel 55 is mounted at one side of or adjacent to the fly-wheel 6 of the motor, this friction wheel being connected to the motor fly-wheel in any suitable way, as for example, through the intermediate friction wheel 56. The shaft 53 has a friction wheel 57 splined thereon, 35 this friction wheel being connected to the shaft 53, but capable of shifting longitudinally thereon. The shaft 53 is provided with a handle 58 by which it may be swung to and from a position to bring the friction wheel 57 on this shaft into frictional engagement with the friction wheel 55, a locking sector 59 being provided to retain the shaft 53 in position where the friction wheel 57 is engaged and disengaged 40 respectively with respect to the friction wheel 55. Means is also provided for shifting the friction wheel 57 relatively to the face of the friction wheel 55. The means shown for this purpose consists in the present instance of a lever 60 which is pivotal at 61, one end of the lever having a fork 62 which coöperates with the friction wheel 57 and the opposite end of the lever is provided with a handle 63 and also with a sector 64 45 for retaining the lever in different set positions. With this arrangement, the friction wheel 57 may either occupy a position at the center of the friction wheel 55 in which case no rotary movement would be transmitted to the shaft 49 or the friction wheel 57 may be shifted to any desired extent to either side of the center of the friction wheel 55, thereby causing motion to be imparted at any desired speed to the shaft 100 50 49 and in either direction to wind or unwind the shaft 135, thus increasing or reducing the tension of the springs for the rear portion of the frame, as circumstances 55 may require. The handles 58 and 63 which control the operation of the power spring regulating means may be located within convenient reach of the driver of the vehicle and the indicator 44 may also be located adjacent to the driver's position on 105 the vehicle. If desired, a power mechanism for regulating the tension of the springs for the front of the frame may be provided similar to that described for regulating the tension of the springs which suspend the 110 rear portion of the frame and also a spring tension indicator similar to that provided for the front spring suspension may also be provided for the rear spring suspension. Means is provided for absorbing shocks between the wheels and the frame. As shown, the shaft 14 is provided with radially projecting pins 65 arranged to engage fixed stops 66 secured within the side members 115 of the frame when the wheels reach a pre- 120 125 130

determined position in proximity to the frame, thus preventing the wheels from colliding with the frame. The individual adjustable heads 32 on the draw rods 5 enables the springs for the respective sides of the frame to be adjusted independently and thus enable the two sides of the frame to be leveled.

Instead of employing means such as that hereinbefore described and which receives its power from the engine to regulate the tension of the springs, means such as that shown in Figs. 11 and 12 may be used by which the driver of the vehicle may from 10 his position on the seat of the vehicle adjust or regulate the tension of the springs. In such cases the rear spring tensioning shaft 135^a which corresponds to the shaft 135 in the previously described construction 15 is provided with a worm wheel 67, a shaft 68 extending longitudinally of the frame of the vehicle, it being journaled in suitable bearings thereon, this shaft having a worm 69 on its rear end which meshes with the 20 worm wheel 67 and the forward end of this shaft 68 is provided with a worm wheel or gear 70 which meshes with a worm 71, the latter being fixed on the lower end of a vertical shaft 72 which is journaled in suitable 25 flanges 73 so that the hand wheel 74 on the upper end of the shaft 72 will be located within convenient reach of the driver of the vehicle while occupying his usual position on the seat. This construction enables the 30 tension or strength of the springs for the rear or load carrying portion of the vehicle to be manually adjusted with facility by the driver, rotation of the hand wheel 74 in the appropriate direction causing rotation 35 of the spring adjusting shaft 135^a to either increase or reduce the tension or strength 40 of the springs to conform with the load on the vehicle, the worms and coöperating worm wheels producing sufficient friction to 45 retain the spring adjusting shaft 135^a in any position into which it may be set.

Figs. 11, 12 and 13 illustrate means whereby the weight of the load contained by the vehicle may be determined, the said means 50 not being illustrated in the other figures in order to prevent confusion and indicate that it may be omitted if desired but it is evident that said means may be applied thereto with equal facility. As shown, the rock shaft 14 55 has a crank or arm 75 fixed thereto, this crank swinging in a forward or rearward direction according to whether the frame of the vehicle descends or rises relatively to the axles, it being understood that the frame 60 of the vehicle will descend to different extents in conformity with the varying loads that may be imposed thereon, the descent of the vehicle frame or body being opposed by the springs. A rod 76 extends forwardly 65 from the arm or crank 75 and the forward

end of this rod carries a wedge or cam 77 which is guided to reciprocate in a forward and rearward direction under the swinging influence of the arm or crank 75. This cam 77 coöperates with a pointer which is preferably provided with a suitable scale which will indicate directly the weight of the different loads applied to the vehicle, the indicator in the present instance comprising a needle 78 which is pivoted at 79 to the rear side of a dial 80, the needle having an extension 81 below its axis which is engaged by the beveled or inclined side of the wedge 77, this extension 81 of the needle being held in engagement with the wedge by a suitable spring 82. The dial 80 has suitable scales 83 to register with the end of the pointer. Preferably the neutral point between the scales is indicated by a zero mark, it corresponding to the normal elevation 85 which the body of the vehicle should occupy. When the load is applied to the vehicle, the body thereof will, of course, descend under the weight of the load, the amount of descent of the body of the vehicle 90 being in accordance with the weight of the load. The amount of descent of the body and hence the weight of the load applied to the body will be indicated by the pointer 78 and the left hand scale with which it co- 95 operates, and in order to bring the vehicle body up to the proper elevation, the hand wheel 74 is rotated to increase the tension on the springs, this increase in tension on the springs having the effect of raising the 100 elevation of the body and when the body has been elevated to the proper level, the pointer 78 will occupy the neutral or zero position on the dial. When the load is removed from the vehicle, the body of the vehicle will rise 105 above its normal height under the action of the springs which support the body. The pointer 78 will then move to the right and coöperate with the right hand scale, the extent of movement of the pointer in this direction depending on the weight of the load 110 previously carried by the vehicle. The vehicle body may then be brought to its normal elevation by rotating the hand wheel 74 in a direction to reduce the strength of 115 the body supporting springs, and when the spring strength has been properly adjusted, the pointer 78 will register with the zero or neutral portion of the dial.

The weighing device just described and 120 which indicates the amount of depression of the body or frame of the vehicle according to the weight of the load thereon is preferably used in conjunction with a device similar to that hereinbefore described for indicating the amount of tension applied to the springs which sustain the weight imposed upon the rear portion of the body. As shown in Figs. 11, 12 and 13, this spring tension indicator comprises a rod 84 which 125

is attached at its rear end to the draw bar 125, this rod is guided to reciprocate longitudinally of the frame and the forward end of the rod carries a wedge-shaped cam 85 which serves to operate a suitable indicator. As shown, this wedge 85 operates upon a pointer 86 which is pivoted at the front of the body on a pivot 87 and coöperates with a suitable dial 88. By this arrangement 10 when the strength of the springs supporting the rear portion of the vehicle body is increased by the spring adjusting shaft 135^a, the draw bar 125 is pulled rearwardly, the rod 84 being also pulled to the rear causing 15 the wedge or cam 85 to act on the pointer, the pointer then indicating the amount of tension applied to the springs. It will be understood that when an increased weight is put on the body, the body descends from 20 its normal height and it is returned to its proper height by operation of the spring adjuster. The body of the vehicle will be maintained always in level position irrespective of the tension applied to the springs, 25 but the height of the body is controlled by the tension of the springs which can be adjusted for loads of different weights. Of course, the body will be restored to its proper height after a load has been removed 30 therefrom by reducing the tension on the springs. In any case, the point 78 of the weighing device indicates whether the body of the vehicle is above or below its proper or normal height, it indicating that the body 35 is at its proper height when the pointer 78 registers with the zero graduation on the dial 80, the conjoint use of the weighing device and the spring tension indicator facilitating adjustment of the springs according 40 to the weight of each load carried by the vehicle.

A vehicle spring suspension embodying the present invention avoids the use of flat or leaf springs and thereby eliminates or 45 reduces to a minimum spring breakages which occur frequently upon vehicles using flat and leaf springs. It also enables the tension of the spring suspension to be regulated to conform with the weight of the 50 load thereon, thus insuring easy or good riding qualities, as compared with the ordinary vehicle spring suspension as heretofore used where the strength of the springs was constant with the result that the springs 55 were usually underloaded or overloaded, the former condition causing the springs to work stiffly, and the latter condition being a frequent cause of breakage of the springs. This regulation of the spring tension, according 60 to the present invention may be effected with facility and the tension to which the springs are set will be indicated to the driver of the vehicle. Furthermore, the tension of the springs for each side of 65 the vehicle may be readily adjusted and in

operation, each wheel will act independently of the other wheels, in consequence of which the vehicle will maintain a level position while the vehicle is passing over rough surfaces.

The amount of resilience afforded by the spring suspension of the present invention will be sufficient, it is believed, to enable solid tires to be used satisfactorily on the 70 wheels instead of pneumatic tires, and also a straight continuous propeller shaft may be used. The frame-work connecting the axles presents the advantage that it securely maintains the axles in parallelism.

By securing the rear axle housing to this 80 frame-work, the latter will sustain the rotative tendency of this axle housing due to the driving or braking force applied to the rear wheels, and hence the necessity of using a torsion arm or torsion tube for the 85 rear axle housing is avoided.

What I claim is—

1. A spring suspension for vehicles comprising a rotatable shaft, bars rigidly connected to said shaft and adapted to be connected to an axle of a vehicle, spring means, and cables connected to said spring means and operating on said shaft to apply a turning force in one direction thereto.

2. A vehicle spring suspension comprising a rotatable shaft adapted to be mounted in a vehicle frame, a pair of bars connected to said shaft to swing about the same in arcs, the free ends of said bars adapted to be connected to an axis, a pair of relatively 100 movable draw bars, one of which is connected to said shaft, means for exerting a pull upon the other draw bar, and springs interposed between the draw bars.

3. A vehicle spring suspension comprising a rotatable shaft adapted to be mounted in a vehicle frame, a pair of members connected to said shaft to swing in arcs as said shaft rotates, the free ends of said members adapted to be connected to an axle of a vehicle, a pair of relatively movable draw bars, one of said draw bars being connected to said shaft, means for setting and holding the other draw bar at different distances from the coöperating draw bar, and springs 110 interposed between the draw bars.

4. A vehicle spring suspension comprising a member for controlling the relative movements between the frame and axle of a vehicle, and means for applying a spring 120 force to said member comprising a pair of draw bars relatively movable in a direction toward and from one another, compression springs interposed between said draw bars, draw rods movably connecting certain of 125 said draw bars to said member, and means for applying and maintaining a pull upon other of said draw rods.

5. A spring suspension for vehicles comprising a member rotatable in response to 130

relative movements between the frame and an axle of a vehicle, and means for applying a spring force to said member embodying a pair of draw bars one of which is 5 operatively connected to said member, means for applying and maintaining a pull upon the other draw bar, springs compressed between said draw bars, and means connected to one of said draw bars for indicating the amount of pull applied thereto.

6. A spring suspension comprising a member movable in response to relative movements between the frame and an axle of a vehicle, a pair of draw bars relatively 15 movable in a direction toward and from one another, springs compressed between the draw bars, draw rods connecting one of said draw bars to said member, other draw rods connected to the other draw bar, and means 20 connected to the latter draw rods for applying a pull thereto.

7. A spring suspension for vehicles comprising a member movable in response to relative vertical movements between the 25 frame and an axle of a vehicle, a pair of draw bars relatively movable toward and from one another, springs acting to relatively separate the draw bars, draw rods adjustably connected to one of the draw bars 30 and operatively connected to said member, and other draw rods connected to the other draw bar and having means for applying a pull thereto.

8. A spring suspension for vehicles comprising a shaft rotatable in response to relative vertical movements between the frame and an axle of a vehicle, a pair of draw bars relatively movable toward and from one another, springs acting to relatively separate 40 the draw bars, cables wound upon said shaft, draw rods connecting said cables with one of said draw bars, a spring-tensioning shaft having cables wound thereon, and draw rods connecting said latter cables with 45 the other of said draw bars.

9. The combination of a vehicle frame and axle, a member on the frame movable in response to relative vertical movements between the frame and axle, a pair of draw bars having springs interposed between them, means connecting one of said draw bars to said member, means for applying a pull to the other draw bar, and an indicator embodying a reciprocating bar connected to 50 the latter draw bar, a cam on said reciprocating bar, a pointer operative by the movements of said reciprocating bar, and a graduated dial co-operative with said pointer.

10. The combination of a vehicle frame 60 and axle, a member on the frame movable in response to relative vertical movements between the frame and axle, means for applying a spring force to said member, and means for regulating said spring force embodying a shaft rotatable to vary such force,

and power means adapted to be operated from the driving motor of the vehicle for rotating said shaft, said power means including gearing adapted to occupy a neutral position and forward or reverse positions for varying the speed ratio with said shaft in either reverse or forward driving relation.

11. The combination of a vehicle frame and axle, a member on the frame movable 75 in response to relative vertical movements between the frame and axle, means for applying a spring force to said member, and means for regulating said spring force embodying a shaft rotatable to vary such force, 80 a friction wheel adapted to be operated by the driving motor of the vehicle, a co-operating friction wheel adapted to be driven in either direction by the friction wheel first mentioned and operatively connected to said 85 shaft, and devices for controlling said latter friction wheel.

12. The combination of a vehicle frame, axles, distance rods connecting the axles, a pair of shafts rotatably mounted in the 90 frame and having spring means acting to turn said shafts in one direction, and pairs of bars connected to the respective shafts to swing in arcs about said shafts as centers, and clevises connecting the free ends 95 of said bars in pairs to the respective axles.

13. A spring suspension for vehicles comprising a rotatable shaft carried by the vehicle frame, a member connected to said shaft and adapted to be connected to one of 100 the axles of the vehicle, said member being adapted to swing in an arc and to rotate said shaft by a relative movement of the vehicle frame toward or from the axle, spring means to rotate said shaft in one 105 direction and thus resiliently support the vehicle frame from the axle, and means for indicating the amount of depression of the vehicle frame and hence the weight of a load applied to the vehicle frame.

110
14. A spring suspension for vehicles comprising a rock shaft carried by the vehicle frame, a bar fixed to the rock shaft and operatively connected to an axle of the vehicle, said member being adapted to swing in an arc and to rotate said shaft by relative movements between the vehicle frame and axle, spring means operative to support the vehicle frame relatively to said axle, an arm or crank connected to said rock shaft, a cam 115 120 operative by swinging movement of said arm or crank, a pointer operative by said cam, and a dial co-operative with said pointer to indicate the extent of depression of the vehicle and hence the weight of a load 125 imposed thereon.

15. A spring suspension for vehicles comprising independent sets of coil springs arranged longitudinally of the vehicle frame, means for communicating the relative move- 130

ments of the vehicle frame toward or from the front axle to one set of said springs and mechanism for transmitting such movements with respect to the rear axle to the 5 other set of said springs.

16. In a spring suspension for vehicles, a set of coil springs arranged longitudinally of the vehicle frame, means for communicating to said springs the relative movements 10 of the vehicle frame toward and from an axle of the vehicle, said means including a rotatable shaft, connections between said

shaft and axle and flexible elements connected to said spring means and operating on said shaft to apply a turning force in 15 one direction thereto.

In testimony whereof I have hereunto set my hand in presence of two subscribing witnesses.

ELMUS E. WEAVER.
